(57) **CLAIM**

The ornamental design for a display screen with virtual three-dimensional shoe icon or display system with virtual three-dimensional shoe icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen with virtual three-dimensional shoe icon in which the shoe icon is shown in a perspective orientation;

FIG. 2 is another front view thereof, showing a side orientation thereof;

FIG. 3 is another front view thereof, showing an opposite side orientation thereof;

FIG. 4 is another front view thereof, showing a front orientation thereof;

FIG. 5 is another front view thereof, showing a rear orientation thereof;

FIG. 6 is another front view thereof, showing a top orientation thereof;

FIG. 7 is another front view thereof, showing a bottom orientation thereof;

FIG. 8 is a front view of a display system with virtual three-dimensional shoe icon shown in a perspective orientation, the virtual three-dimensional shoe icon being the same design as shown in the first embodiment of FIGS. 1-7; FIG. 9 is another front view thereof, showing a side orientation thereof;

FIG. 10 is another front view thereof, showing an opposite side orientation thereof;

FIG. 11 is another front view thereof, showing a front orientation thereof;

FIG. 12 is another front view thereof, showing a rear orientation thereof;

FIG. 13 is another front view thereof, showing a top orientation thereof; and,

FIG. 14 is another front view thereof, showing a bottom orientation thereof.

(Continued)

In FIGS. 1-7, the outermost broken line represents a display screen which forms no part of the claimed design. In FIGS. 8-14, the outermost broken line represents a portion of a field of view for a visual display and forms no part of the claimed design. In FIGS. 1, 6, 8, and 13, the broken lines inside of the outermost broken line represent portions of the shoe icon which forms no part of the claimed design. The icon in FIGS. 1-14 is shown in various orientations to provide an understanding of the three-dimensional appearance of the design.
